UNITED STATES PATENT OFFICE

99,514

DESIGN FOR A BATTERY BOX

Raymond Le Clercq, Los Angeles, Calif.

Application February 11, 1936, Serial No. 61,089

Term of patent 14 years

To all whom it may concern:

Be it known that I, Raymond Le Clercq, a citizen of the United States, residing at Los Angeles, in the county of Los Angeles and State of California, have invented a new, original, and ornamental Design for a Battery Box, of which the following is a specification, reference being had to the accompanying drawing, forming part thereof.

The figure is a perspective view of a battery box showing my new design.

The side of the battery box not visible is identical with that shown on the right hand side, and the rear is identical with the front with the exception that the circular shield is absent and the median horizontal ribs extend clear across.

I claim:

The ornamental design for a battery box as shown.

RAYMOND LE CLERCQ.
